UNITED STATES PATENT OFFICE

2,651,188

AIR CIRCULATING COOLER HAVING A PLURALITY OF ICE COMPARTMENTS

Ralph W. Rhoads, Sr., Springfield, Mo.

Application December 17, 1951, Serial No. 262,122

5 Claims. (Cl. 62—131)

1

This invention relates generally to an air cooler, and more particularly a cooler for cooling the air within a cold storage box by the use of Dry Ice.

The primary object of this invention is to provide an improved air cooler in which the air is passed through a sinuous conduit which is adjacent compartments for receiving Dry Ice.

Another object of this invention is to provide an improved air cooler in which the air is circulated through a conduit adjacent a cooling medium by a blower.

Another object of this invention is to provide an improved air cooler which is of simple construction and may be easily and economically manufactured.

A further object of this invention is to provide an improved air cooler in which the air conduit forms a material portion of the storage compartment for Dry Ice.

With these objects definitely in view, this invention resides in certain novel features of construction, combination and arrangement of elements and portions as will be hereinafter described in detailed specification, particularly pointed out in the appended claims, and illustrated in the accompanying drawings which form a material part of this application, and in which:

Figure 1 is a side elevational view of a truck trailer in which is mounted the improved air cooler, which is the subject of this invention, parts being broken away and shown in section, and showing the arrangement of the air cooler with respect to the trailer;

Figure 2 is a side elevational view of the improved air cooler, one side being omitted, and parts being broken away and shown in section, and showing the construction and arrangement of the air conduit;

Figure 3 is a horizontal transverse sectional view through the air conduit and taken substantially upon the plane indicated by the section line 3—3 of Figure 2 and showing the arrangement of partitions within the air conduit;

Figure 4 is an enlarged partial transverse vertical sectional view taken substantially upon the plane indicated by the section line 4—4 of Figure 2 and showing the arrangement of the ice receiving compartments with respect to the air conduit, and the manner in which the Dry Ice is stored therewithin;

Figure 5 is an enlarged partial transverse vertical section view taken substantially upon the plane indicated by the section line 5—5 of Figure

2

1 and showing the construction of the door for the ice compartments; and

Figure 6 is an enlarged partial top plan view showing drive means for a blower which is installed in series with the air conduit.

Similar characters of reference designate similar or identical elements and portions throughout the specification and throughout the different views of the drawings.

Referring now to the drawings in detail, this invention includes a truck trailer, which is referred to generally by the reference numeral 10. The truck trailer 10 is provided with the conventional type of insulated walls 12 to provide an insulated compartment 14 which may be used for refrigerated storage. The rear underside of the trailer 10 is provided with a conventional running gear 16, and the trailer 10 is pulled by a conventional tractor 18, the rear part only of the tractor being shown. The trailer 10 is connected to the tractor 18 by a conventional fifth wheel 20. Mounted within the trailer 10 is an improved air cooler, which is the subject of this invention, and will be described in detail hereinafter.

Referring to Figure 2 in particular, it will be seen that the improved air cooler 22 includes a sinuous air conduit 24 and a plurality of ice compartments 26. The air conduit 24 is formed with a plurality of horizontal portions 28 which form the top and bottom side walls of the ice compartments 26. Connecting the horizontal portions 28 are a plurality of integral vertical portions 30 each which forms one of the end walls of each ice compartment 26.

Referring now to Figure 4, it will be seen that the side walls of the ice compartments 26 are formed by a plurality of parallel plates 32 which extend between and are secured to the horizontal portions 28 of the conduit 24. Closing the other ends of the ice compartments 26 are a plurality of doors 34. The air conduit 24 in combination with the plates 32 and the doors 34 form a plurality of substantial air tight ice receiving compartments. The walls of the ice receiving compartments 26 are substantially air tight in order to prevent the rapid evaporation of Dry Ice 36 stored therewithin resulting when same is exposed to air.

Referring again to Figure 2, it will be seen that the lower free end of the air conduit 24 is provided with an enlarged intake opening 38. The upper end of the air conduit 24 is provided with a special fitting 40, whereby the air conduit 24 is connected to the side wall 42 of a squirrel

cage type blower 44. The other side wall 46 of the blower 44 is provided with a conduit 48 which communicates with the interior of the uppermost horizontal portion 28 of the air conduit 24 through an opening 50 therein. The cold air is discharged from the blower 44 through a conventional blower outlet 52.

Referring now to Figures 3, 4 and 5 in particular, it will be seen that the Dry Ice 36 is provided in the form of blocks whereby it may be conveniently stored within the ice receiving compartments 26. The air conduit 24 is divided into a plurality of smaller parallel air conduits 54 by a plurality of vertical longitudinally extending partitions 56. The partitions 56 extend between and are secured to the upper and lower walls of the conduit 24. In order that turbulences may be set within the air conduit 24 to insure equal cooling of all the air passing therethrough, the partitions 56 are corrugated with the corrugations extending longitudinally of the air conduit 24.

Referring now to Figures 2 and 5, it is seen that the doors 34 are of an insulated construction and include metal front faces 58 and insulating sheets 60. The rear edges of the doors 34 are provided with sealing gaskets 62 which engage the walls of the air conduit 24 to provide a tight seal between the doors 34 and conduit 24. The doors 34 are provided with handles 64 for opening and closing the same.

Referring now to Figures 1 and 6 in particular, it will be seen that the trailer 10 has mounted on its front wall 66 an exterior compartment 68. Mounted within the compartment 68 is a motor, which may be either electrical or gasoline powered. The motor 70 is provided with a drive shaft 72 which extends through the front wall 66 of the trailer 10 and is connected to the blower 44 for driving the same. As shown in Figure 6 particularly, it will be seen that the blower 44 is provided with a shaft 74 which is at right angles to the motor shaft 72 and that the shafts 72 and 74 are provided with bevel gears 76 and 78, respectively, which are in engagement with each other. The blower shaft 74 passes through the fitting 40 through a special air tight fitting 80.

In view of the foregoing, it will be seen that due to the influence of the blower 44, air within the refrigerator compartment 14 of the trailer 10 will be drawn through the inlet opening of the conduit 24. The air will then pass through the conduit 24 over and around the ice compartments 26 whereby it is cooled to a low temperature by Dry Ice 36 stored within the ice compartments 26. The cool air will then pass out of the air conduit 24 through the blower outlet 52 back into the refrigerating compartment 14. Since this cycle is continuously repeated, it is obvious that the air within the refrigerating compartment is substantially equal to the temperature of the vapor within the ice compartments 26.

The type of air cooler shown and described herein makes the use of a cheap but highly effective refrigerant to produce the same results as a complicated refrigerator unit. Furthermore, since the air cooler described herein is not entirely dependent on power means for operating the same, it is obvious that perishable goods stored within the refrigerator compartment 14 are not subject to damage due to mechanical breakdown.

In view of the foregoing, it is thought that

the operation of this machine will be readily understood, and further description would appear to be unnecessary. Minor modifications of the cooler varying in minor details from the embodiment of the cooler illustrated and described here, may be resorted to without departure from the spirit and scope of the invention, as defined in the appended claims.

Having described the invention, what is claimed as new is:

1. An air cooler for a cold storage box comprising a plurality of ice receiving compartments, an air conduit adjacent said ice receiving compartments, means for circulating air through said conduit, said air conduit being provided with a plurality of vertical continuous partitions to divide said air conduit into a plurality of separate conduits, said partitions being provided with longitudinally extending corrugations in order to insure turbulence of air passing through said conduit.

2. An air cooler for a cold storage box comprising a plurality of ice receiving compartments, an air conduit adjacent said ice receiving compartments, means for circulating air through said conduit, said air conduit being provided with a plurality of vertical continuous partitions to divide said air conduit into a plurality of separate conduits, said partitions being provided with longitudinally extending corrugations in order to insure turbulence of air passing through said conduit, said air conduit being sinuous and forming the top, bottom and one end wall of each of the compartments.

3. An air cooler for a cold storage box comprising a plurality of ice receiving compartments, an air conduit adjacent said ice receiving compartments, a blower for circulating air through said conduit, one end of said air conduit terminating in a continuous loop, said blower being mounted in said loop and having dual intake openings to permit circulation of air through said loop in opposite directions.

4. An air cooler for a cold storage box comprising a plurality of ice receiving compartments, an air conduit adjacent said ice receiving conduits, a blower for circulating air through said conduit, one end of said air conduit terminating in a continuous loop, said blower being mounted in said loop and having dual intake openings to permit circulation of air through said loop in opposite directions, said blower being driven by a power unit mounted exteriorly of said cold storage box.

5. An air cooler for a cold storage box comprising a sinusoidal air conduit forming portions of a plurality of ice receiving chambers, plates secured to sides of said conduits forming sides of said chambers, staggered end doors closing open ends of said chambers between adjacent end portions of said conduit, said conduit being formed by a single tubular member.

RALPH W. RHOADS, SR.
